RADIANT BASEBOARD PANEL OR THE LIKE

Filed Sept. 13, 1944

Inventor:
John P. Magos

By: Joseph O. Lange Atty.

UNITED STATES PATENT OFFICE

141,145

DESIGN FOR A RADIANT BASEBOARD PANEL OR THE LIKE

John P. Magos, Wilmette, Ill., assignor to Crane
Co., Chicago, Ill., a corporation of Illinois

Application September 13, 1944, Serial No. 115,290

Term of patent 14 years

(Cl. D81—21)

To all whom it may concern:

Be it known that I, John P. Magos, a citizen of the United States, residing in the county of Cook, village of Wilmette, State of Illinois, have invented a new, original, and ornamental Design for a Radiant Baseboard Panel or the like, of which the following is a specification, reference being had to the accompanying drawing forming part thereof.

Fig. 1 is a front perspective view of a radiant baseboard panel or the like embodying my new design.

Fig. 2 is a rear perspective view of the same.

I claim:

The ornamental design for a radiant baseboard panel or the like, substantially as shown.

JOHN P. MAGOS.
